SCALE

George Walker and John Earl Woodland, Brooklyn, N. Y., assignors to The Jacobs Bros. Co., Inc., Brooklyn, N. Y., a corporation of New York

Application March 21, 1929, Serial No. 348,754

5 Claims. (Cl. 265—59)

This invention relates to a functional and structurally improved scale particularly of the platform type and by means of which even balance and over or under weight conditions will be registered in such manner as to be plainly apparent to the operator.

A further object of the invention is that of constructing a device of this type in which the parts will seek normally to maintain an evenly balanced condition, and in which, furthermore, the several parts employed will be each individually simple and rugged in construction and be capable of being readily assembled and set up to provide a scale operating over long periods of time with freedom from mechanical difficulties, and which scale, furthermore, may be sold at a relatively nominal price.

Another object is that of furnishing mechanism which may be associated readily with a finished scale, so that, if desired, platform scales, as heretofore constructed, may be advantageously combined with mechanism falling within the province of the present invention.

With these and other objects in mind, reference is had to the attached sheets of drawings illustrating practical embodiments of the invention and in which

Fig. 1 is a partly fragmentary sectional front view of one type of scale mechanism.

30. Fig. 2 is a perspective view of certain details of the mechanism shown in Fig. 1.

Fig. 3 is a partly fragmentary sectional front view of another form of scale mechanism.

Fig. 4 is a perspective view of certain details 35 of said mechanism, and

Fig. 5 is a partly fragmentary sectional front view of a still further form of scale mechanism.

With a view to avoiding unnecessary illustration, only a portion of a platform scale has been 40 shown in the accompanying drawings, it being appreciated that mechanisms of this nature are well known to those conversant with the art, and that the mechanisms thereof are generally similar, the present invention being capable of application to various types of structure.

Thus, in Fig. 1 the numeral 5 indicates the column or post commonly extending from the rear edge of the base which supports the platform, and which latter is connected to move 45 an actuating rod 6. Secured to the upper end of the post or column 5 is the usual type of support 7, providing at its outer end a confining guide 8, within the slot of which the free end of the lever 9 moves. Supported upon this lever is a 50 poise 10, shiftable to register with any of the

graduations appearing upon the face thereof, and this lever may be, in turn, supported upon knife edges 11 and have its rear end terminating in a pair of upwardly extending spaced arms 12. Mounted between the arms, and preferably upon 5 a screw-threaded rod 13, is an adjusting or setting weight 14, and the actuating rod 6 may be suitably connected to the inner end of the lever, the movements of which latter may be damped by a dash-pot 15.

The foregoing structure is illustrative, and not to be strictly interpreted. When the invention is employed in connection with a scale of this character, it is preferred that a housing 16 be mounted upon the support 7, and this housing has at its 15 upper end an opening within which there is displayed a scale or chart 17, the range of which is traversed by a pointer 18. This pointer may, as shown in Fig. 2, be formed of a strip bent upon itself to furnish adequate rigidity, and the lower 20 end thereof is secured to the supporting element 19, through which a pin 20 extends, the ends of which pin are properly carried within the housing 16. A pair of spaced arms 21 form a part of the supporting member 19, and mounted between 25 them is the upper end of a link 22, the lower end of which is pivotally connected, as at 23, to the beam. Also, the supporting member 19 may have, as a part of its body, a counter-weight 24, serving to balance the weight of the pointer. 30

In a construction of this nature the scale may be operated in the conventional manner, and during the movements of the beam incident to such weighing operation, the registering mechanism aforescribed will have a somewhat magnified movement incident to the structure employed. Thus, an operator will be in a position to observe instantly whether the scale is in an evenly balanced condition, and, due to the fact that this mechanism is connected to the beam 40 adjacent its point of mounting, a minimum of resistance will be offered to the beam movements.

With a structure of this nature, it is usually desirable to provide means whereby the parts 45 will normally tend to maintain an evenly balanced condition. Furthermore, it is desirable that the amount of over or under weight be registered accurately. Thus, a resilient element is employed, and, as illustrated, this element takes the 50 form of a flexion strip 25, the lower end of which is slotted. A screw 26 extends through this slot and secures the strip to one of the arms 12, the strip being free to slide through the extent of the slot, but being held from displacement by the 55

head of the screw. The upper end of this element extends into a casing 27, mounting a pair of opposed pins 28, to engage one with each of the opposite faces of the strip 25, it being noted that by having the strip adjacent the point of mounting of the beam, most desirable results are achieved.

Now, referring to the structures shown in Figures 3 and 4, it will be noted that the reference numerals 5 to 18 inclusive, have been applied to the same parts designated by the corresponding parts in the preceding numerals. In this form of structure, however, the beam carries a post 29 which extends into the housing 16 and this post mounts at its upper end a link 30. The lower end of the pointer 18 is mounted by a suitable clamping structure 31 upon the upper end of a flexion strip 32 the lower end of which is clamped as in 33 to a bracket 34. The latter is adjustably secured to the casing 16 in any desired manner as, for example, by employing a slot and bolt structure 35.

It is obvious in the form of construction illustrated as the beam oscillates the post will traverse an arc which will result in the link being reciprocated. Such movement on the part of the link will cause an oscillation of the pointer to traverse the graduations of the dial 17. Thus, over and under weight will be indicated in a magnified manner and moreover the amount of such over or under weight will be registered—the resistance to deflection offered by this strip assuring this result.

Referring to Figure 5, it will be noted that the registering mechanism has been shown in association with the outer end of the beam 9. Accordingly, the casing 16 is positioned adjacent the outer end of this beam and in the illustrated embodiment this casing pivotally mounts the pointer 18 as at 36. The side of the pointer is counterbalanced as desired as at 37 and an extension 38 is pivotally connected to a link 39 the lower end of which is simultaneously connected to the outer end of the beam. It will be apparent in this structure that the desired results are also achieved in that as the outer end of the beam oscillates corresponding movement on the part of the pointer will follow. As shown, a flexion strip may be secured to the casing at one end and coupled by means of a series of link connections to the outer end of the beam for offering increased resistance to the movement thereof.

From the foregoing it will be appreciated that among others the several objects of the invention specifically aforementioned have been achieved. It is, moreover, apparent that numerous changes in construction and re-arrangement of the parts might be resorted to without departing from the spirit of the invention as defined by the claims.

60 We claim:

1. In combination, a scale of the platform type including a frame, a poise mounting beam, means supported by said frame and pivotally mounting said beam to one side of its center, means connecting the short arm of said beam to a load receiving platform, means connected to said frame

and to said beam adjacent the point of pivotal mounting of the latter to offer increased resistance to movement of said beam beyond an evenly balanced condition, and registering means also connected to said beam for registering the amount of deflection of said beam beyond an evenly balanced condition.

2. In combination, a scale of the platform type including a frame, a poise mounting beam, means supported by said frame and pivotally mounting said beam to one side of its center, means connecting the short arm of said beam to a load receiving platform, a flexion strip having its ends respectively connected to said frame and to said beam adjacent the point of pivotal mounting of the latter, said strip tending normally to maintain said beam in an evenly balanced condition, and a pointer for registering the amount of deflection of said strip and the consequent deflection of said beam from a balanced condition. 20

3. In combination, a scale of the platform type including a frame, a poise mounting beam, means supported by said frame and pivotally mounting said beam to one side of its center, means connecting the short arm of said beam to a load receiving platform, a flexion strip having one of its ends secured to said beam and adjacent the point of pivotal mounting of the latter, means connected to said frame and cooperating with the opposite end of said strip to maintain said beam in an evenly balanced condition, and registering mechanism connected to said beam for indicating the amount of deflection of the latter beyond an evenly balanced condition. 25

4. In combination, a scale of the platform type including a frame, a poise mounting beam, means supported by said frame and pivotally mounting said beam to one side of its center, means connecting the short arm of said beam to a load receiving platform, a flexion strip having one of its ends secured to said beam and adjacent the point of pivotal mounting of the latter, a pair of opposed members mounted by said frame and to engage said strip adjacent its opposite end whereby to normally maintain said beam in an evenly balanced condition, and a registering mechanism connected to said beam to indicate the amount of deflection of the latter from an evenly balanced condition. 40

5. In combination, a scale of the platform type including a frame, a poise mounting beam, means supported by said frame and pivotally mounting said beam to one side of its center, means connecting the short arm of said beam to a load receiving platform, a flexion strip having one of its ends connected to said frame, the body of said strip extending substantially vertically above said beam and at right angles thereto, means connecting the free end of said strip to said beam whereby to normally maintain said beam in an evenly balanced condition, and means connected to said strip to indicate the amount of deflection of said beam from such evenly balanced condition. 50
